UNITED STATES PATENT OFFICE.

BENJAMIN F. ERWIN, OF FAIRFAX, MISSOURI.

SNOW-PLOW.

1,243,926.

Specification of Letters Patent. Patented Oct. 23, 1917.

Application filed May 16, 1916. Serial No. 97,860.

To all whom it may concern:

Be it known that I, BENJAMIN F. ERWIN, a citizen of the United States, residing at Fairfax, in the county of Atchison and State 5 of Missouri, have invented certain new and useful Improvements in Snow-Plows, of which the following is a specification.

The present invention has relation to certain new and useful improvements in snow 10 plow apparatus, and it contemplates, primarily, the provision of a novel device of this nature, wherein the plow structure proper is adjustable, thus enabling the same to be used on rough and uneven surfaces 15 and obviating the danger of breakage of the blades due to their contacting with stones and other structures on the roadway.

A still further object of the invention is to provide a device of the type in question 20 that is extremely simple in construction, strong and durable, and highly practical from both the standpoint of the manufacturer and the standpoint of the user; and which, it is believed, may be manufactured 25 at a minimum cost.

Various other objects and advantages will become apparent during the continuance of the following description.

These objects are accomplished by such 30 means as are shown in their preferred form in the accompanying drawings, described in the following specification, and then more specifically pointed out in the appended claims.

35 In the accompanying drawings wherein like characters designate like parts throughout the several views;—

Figure 1 is a view in top plan showing my improved snow plowing apparatus as in 40 its preferred embodiment;

Fig. 2 is a view in side elevation;

Fig. 3 is a view in bottom plan of the forward end of the device showing more clearly the relative position of the plow structure, 45 proper;

Fig. 4 is a view of the plow structure proper, which in the present embodiment consists of a plurality of radial plow blades; and

50 Fig. 5 is a view in section of the plow structure proper.

My invention, in its present embodiment, consists generally of a forward and carrying platform 10 which rests upon and is supported by an axle 11, that has its skein por-

tions passed through the hubs of the supporting wheels 12 and 13, respectively. The platform 10 carries spaced brackets 14 upon its under face bearing against the sides of the axle 11 and which serve to prevent independent longitudinal movement of the platform with respect to the axle. However, by reason of its construction, it is apparent that the platform may be tilted, so as to raise or lower the outer end thereof. 60

To the platform 10 is affixed a pair of spaced bearing members 15 and 16 in which is journaled a driven shaft 17, the latter having one end projecting beyond the forward edge of the platform and its rear end 70 projecting beyond the rear edge of the platform. Beyond the forward edge of the platform, the shaft 17 carries a drum 18, (see Fig. 4), from which radiates a plurality of blades 19; the blades being connected 75 through the instrumentality of protecting plates 20 and having their free ends projecting beyond the circumferential edge of the plates 20 and curved to form lips 21. Braces 22 are also employed, one end of 80 each brace being connected to one of the blades 19, and the other end of each brace being suitably connected to the respective one of the plates 20. By this arrangement, it will be noted that the blades will be held 85 in a rigid position at all times with respect to the drum 18 and the plates 20, thus insuring the longevity of the device.

The inner one of the plates 20 carries a bevel gear 23, which, as shown in Fig. 1, 90 meshes with a bevel gear 24 carried upon the stub-shaft 25. The stub-shaft 25 is journaled through spaced bearing members 26 that are carried on the platform 10, and also carries a pulley 27 which may be driven 95 from a source of power 28 by means of a belt 29. Consequently it will be seen that upon rotation of the stub-shaft 25, the desired movement will be imparted to the plow structure, rotating the plates 20, and causing the blades to operate so as to throw the snow to the side of the road or highway. While, in the drawings, I have shown a combustion engine 28, as furnishing the power to drive the rotary plow structure, it is to 100 be appreciated that I am not limited to this particular means and that electricity or other medium may be employed, if it is so desired.

With a view of providing means to move 110

the plow structure, forwardly and at the same time permit the vertical adjustment thereof, I provide a rear frame or supporting structure 30, which is carried upon an 5 axle 31 and the axle 31 is in turn supported by means of wheels 32. A bar 33 extends forwardly of the frame 30, and is passed through a U-shaped bracket 34 of the platform 10. The bar 33 carries a cross head 35, 10 which is in turn equipped with suitable whiffletrees 36, which enables the operator to use draft animals to propel the plow structure.

Adjacent the forward end, the bar 33 has 15 provided thereon side pieces 37 and 38, as at 39, the side pieces passing through the U-bracket 34 of the platform 10 and pivotally connected with the said bracket by means of a horizontal pin 40; the pin 40 20 also passes through a block 41 carried between the side pieces 37 and 38, clearly shown in Fig. 3.

I further equip the frame 30 with a vertical standard 42 which has a segmental rack 43 provided thereon as illustrated in 25 Fig. 2. An actuating lever is pivotally mounted on the standard as at 45, and has a pawl 46 coöperating with the rack 43. The pawl 46 is operated by means of the pivoted 30 link 47 the link being mounted in proximity to the hand grip of the operating lever 44, as is obvious. At its lower free end the operating lever 44 carries another link 48 as at 49, this said link serving a purpose which 35 will hereinafter be made apparent. A rearwardly directed pipe 50 is telescopically mounted on the driven shaft 17, above the bar 33 and carries at its rear end, a bracket 51 that has a ring 52 receiving the standard 42. The link 48 is pivotally connected with 40 the depending ear 53 of bracket 51, as at 54, thereby movement of the operating lever will cause the adjustment of the pipe 50 and the consequent movement of the plat- 45 form 10.

In conjunction with the above, I also provide improved means whereby the proper guiding of the plow may be effected. In carrying this into effect, I provide the main 50 axle 11 with stub-axles 11', the latter in turn carrying rearwardly directed arms 12'. A link 13' is then provided to loosely connect the arms just referred to and means are further provided to actuate the link and there- 55 by effect the uniform adjustment of the stub-axles and the supporting wheels 12 and 13 carried thereby.

A bracket 14' is mounted on the under- 60 side of the platform 10 and pivotally supports an operating lever 15' as at 16'. One end of the lever is provided with a slot 17' that receives a pin 18' of the cross link 13', while the other end is provided with a hand grip 19' whereby it may be conveniently 65 manipulated. From the above it will be

readily seen that the shifting of the free end of the lever 15' causes lateral movement of the link 13' and the consequent uniform adjustment of the supporting wheels of the 70 plow.

The operation of my device is as fol- 75 lows;—

When the parts are arranged as in Fig. 2, the plow structure may be rotated in the desired manner, but if for any reason the operator desires to raise the plow structure, the pawl 46 is first drawn from the seg- 80 mental rack 43 and the raising of the free end of the operating lever 44 will cause the downward movement of the rear end of the pipe 50, and the consequent tilting of the platform 10. The platform 10, tilting rear- 85 wardly causes the upward movement of the plow structure, while it will be noted that the pivot pin 40 that passes through the brackets 34 compensates for the independ- 90 ent movement of the front and rear frames 10 and 30, respectively. On the other hand, by pressing downwardly on the free end of the lever 44, the platform 10 may be brought to a normal position, or if this pressure is continued, it will be operated so as to tilt the platform forwardly.

From the foregoing, it is believed that 95 the advantages and novel features of my in- vention will be understood, and therefore, further detailed description is deemed unnecessary.

In reducing the invention to practice, it 100 will be found that the form herein referred to as the most practical and preferred em- bodiment is the most efficient, but in con- currence with the adoption of the device, it 105 is emphasized that various minor changes in the details of construction and in the proportion of parts may be resorted to when required without sacrificing any of the ad- vantages of the invention, as defined in the 110 appended claims.

Having thus fully described the invention 110 what is claimed as new, and desired to be secured by Letters Patent, is;—

1. In a device of the character described a carriage having a forward truck including a platform and an axle pivotally mounting 115 the platform, and a rear truck having a tongue pivotally connected with the plat- form of the forward truck, a rotatable op- erating element having a supporting shaft rotatably mounted in bearings upon said 120 platform, a standard carried by said rear carriage, a lever shaft in telescoping engage- ment with the supporting shaft and having a handle element at its rear end slid- 125 able upon the standard, and means to releasably hold the handle element in an adjusted po- sition upon the standard.

2. In a device of the character described, a carriage having a forward truck including a pivoted platform and a rear truck having 130

a forwardly extending tongue pivotally connected with the platform, an operating element having a shaft rotatably connected with the platform, a standard extending 5 above the rear truck, a lever shaft slidably engaging the first mentioned shaft and having a handle element slidably upon said standard, an adjusting lever pivoted to said standard, and a link connecting the adjust-

ing lever with the handle element of the 10 lever shaft.

In testimony whereof I affix my signature in presence of two witnesses.

BENJAMIN F. ERWIN.
